DRIVEN FASTENER

Robert Lay Hallock, 32 Vine Road, Larchmont, N.Y.
Filed Nov. 28, 1958, Ser. No. 777,108
6 Claims. (Cl. 85—28)

This invention relates to roof construction including a deck or supporting structure and relatively thick insulation attached thereto, and more particularly to the attaching means by which such insulation is secured to the roof deck or supporting structure regardless of whether it is flat, inclined, or of metal or wood, such insulation or Fiberglas or other material having the characteristic of resiliency or the ability to spring back after being subjected to pressure and such pressure is relieved.

The invention further relates to roof construction in which insulation of, for example, from approximately $\frac{1}{2}$ " to 3" thick is bonded to the roof deck or supporting structure and layers of felt or tar paper are bonded together by hot asphalt or tar and in which roof structure the insulation in slab or other form is resilient being composed of relatively dense fiber which can be adhesively attached or secured in place by ordinary nails or fasteners or by special nails or fasteners such as disclosed in copending application 516,684.

Insulation used in roof construction may be of any desired character such as Fiberglas, or other fiber or the like pressed into slabs to which is glued a layer of heavy felt. A slab of this type of roof insulation is unlike that made solely from wood fiber in that it is sponge-like and easily compressible, its layers may be easily separated, and since it is elastic it springs back or returns to its original shape after a compressing force is removed. Because of its particular characteristics Fiberglas roof slabs cannot be satisfactorily secured by adhesive to a roof because the layers separate in a high wind permitting the top layer or layers to blow away. If it is nailed down using conventional nails with large or small heads, the heads pull through the layers of felt when the glass wool fibers are compressed whether by the feet, wheel barrows, or weight from ice or snow.

It is an object of the invention to provide a mechanical fastener in the form of a special nail which can be used for positively securing insulation, of resilient or springy character and capable of being compressed but which will return to its normal position when the pressure is removed, upon the surface of a deck or support of metal, wood or other substance and in which the head of the nail can move downwardly on its shank when the material is compressed and which cannot move upwardly above or beyond a fixed predetermined surface level of the insulation.

Another object of the invention is to provide guide means between a movable head and the shank of a nail so that the head will at all times remain perpendicular to the shank while movable axially of the shank.

Another object of the invention is to provide a nail head having a completely closed and concealed well within the same from which hot asphalt or tar are excluded and therefore cannot restrict the connection between the shank and the movable head.

A further object of the invention is to provide a headed fastener which can be rigidly secured to a wood or metal deck and by means of which flexible or resilient insulation can be fastened tightly against the surface of the deck in a manner to permit the surface of the insulation as well as the nail head to be depressed simultaneously relative to the shank of the nail with the opening through which the nail is applied sealed at all times, and in which the head of the fastener is provided with a tubular extension and of stepped diameter in order that the nail

2

or tubular extension may gradually penetrate rather than abruptly enter the insulation and create an opening of excessive size.

A further object of the invention is to provide a fastener 5 having a shank with a small integral head and a larger hollow head with a well receiving the smaller head and reciprocable theron and which fastener can be applied by using a conventional hammer and without special tools and in which the small integral head on the end of the 10 shank will be located in the bottom of the well in the large head so that when the intimately united insulation and large nail head are depressed they may move downwardly on such shank.

A further object of the invention is to provide a fastener 15 of the character indicated for attaching resilient insulation such as Fiberglas or the like to a metal or wood roof deck so that the head of the nail will be flush with the upper surface of the insulation while the small integral head on the end of the shank will be located 20 in the bottom of the well of the movable head, and due to the structure of the fastener its shank can be driven through the relatively thick resilient insulation but its large head cannot be driven therethrough.

A further object of the invention is to provide a driven 25 fastener having an enlarged auxiliary head with a tubular section of stepped diameters and an axially movable shank with a smaller integral head on one end and a penetrating point on the other with the smaller head within the enlarged head, whereby the heads are free to move relative 30 to each other a predetermined amount, as well as a head structure in which the edges are rolled upward to prevent sharp edges cutting into the felt of the roof insulation slab. This upward turned edge also simplifies 35 automatic assembly of the nail parts in manufacturing.

Other objects and advantages of the invention will be apparent from the following description taken in conjunction with the accompanying drawing wherein:

FIG. 1 is a perspective illustrating one application of 40 the invention for use in a deck of metal.

FIG. 2, a section illustrating the manner of fastening insulation to a sheet metal deck;

FIG. 3, a modified form of fastener;

FIG. 4, a vertical section on the line 4—4 of FIG. 3;

FIG. 5, a perspective illustrating a plurality of integral 45 fasteners;

FIG. 6, a perspective of a slightly different form of fastener head; and

FIG. 7, a perspective illustrating a form of invention 50 for use in a wood, or the like, deck.

Briefly stated the invention is a driven fastener having a shank with an elongated driving point at one end and an integral head at the other. For use with a metal deck the shank is tapered slightly for a portion of its length 55 from its driving point and such tapered portion is provided with grooves the walls of which are disposed reversely of the taper to provide cutting edges which cause a solid joint with a metal deck or the like support. For use with a wood deck the shank preferably is of uniform diameter with or without grooves therein adjacent the point end for increasing its holding power in wood with vertical grooves adjacent its head end having a smooth close fit to permit movement between the shank and the tubular section of the head. The device is provided with an enlarged movable auxiliary head having a well or chamber in which the integral head is slidably sealed. When the auxiliary head is in contact with the integral head a blow on the auxiliary head will force the shank into the insulation and deck material. The auxiliary head is provided with a tubular extension of stepped diameters the section of larger diameter retaining and controlling the relative movement of the heads and the

section of smaller diameter guiding and holding the nail shank perpendicular to the head at all times and in a manner so that the head will move with the insulation material to compensate for the compression thereof.

With continued reference to the drawing the nail or driven fastener of the present invention is intended for use in securing a layer of relatively resilient or compressible insulating material directly against a support which may be a deck of wood, metal or other material, such nail or fastener comprises a shank 10 with an elongated tapered end providing a driving point 11 and a tapered portion 12 adjacent such driving point. The shank is provided with substantially horizontal or annular grooves forming cutting edges adjacent such driving point with annular or spiral grooves as illustrated in FIG. 1.

The remote end of the nail from the driving point is provided with an integral head 13 reciprocable within a well or chamber of an enlarged auxiliary head 14. The auxiliary head is movably associated with the shank in order that the surface of the material to be held down may be depressed slightly whereupon the nail head will move down with it and then upwardly with it when the pressure is removed, the nail being intended to be used in the securing of compressible material of sufficient resiliency to yield the amount required and thereafter to return to its initial position.

The auxiliary head may be composed of metal, plastic or other suitable material of sufficient strength and toughness to withstand the force to which it is subjected when utilized in the manner indicated. Also it may be of any desired configuration, a circular head having been found particularly appropriate and satisfactory.

In order to provide a substantial bearing between the auxiliary head and the shank regardless of the relative positions of the same the bottom of the cup is provided with a reduced extension 15 providing an extended reinforced bearing surface for cooperation with the shank 10, to maintain the top of the auxiliary head and shank in perpendicular relation to facilitate application of the fastener. The spaces between the steps are small and provide a gentle transition to offer little resistance to the application of the nail through the insulation material.

The auxiliary head is provided about its upper portion with an outwardly extending flange 17 which may be of circular or other desired configuration, such flange being adapted to provide a large area to bear against the upper surface of the material 18, held down by the nail or fastener. The marginal portion of the flange 17 is provided with an upwardly and inwardly turned portion 19 overlying and retaining a cap forming disk 20 in place and in a manner to completely seal the well in the auxiliary head 14. The cap 20 has a raised central portion 21 against which the head 13 is adapted to engage when the nail or sheet penetrating fastener is driven into the material and also when the movement of the material permits the head to lower.

In the driving of the nail into a metal deck the head 13 will be against or in contact with the underside of the cap 21 and upon the top of the cap being struck with a hammer, force will be imparted endwise of the shank 10 to cause it to penetrate the material 18 and the metal or wood deck 22.

In FIG. 2 a pair of the driven fasteners are disclosed, the one to the left disclosing the material compressed by the impact of a hammer 23 with the auxiliary head lower than the surface of the insulation material. In this figure the driven fastener at the right reveals the position of the auxiliary head after the hammer pressure has been removed, the shank and integral head remaining in the same position as in FIG. 1.

Instead of the auxiliary head of the nail or driven fastener being of the character disclosed in FIGS. 1 and 2 it may be of the character disclosed in FIGS. 3 and 4 in which an auxiliary head 24 has a flange 26 of polygonal

configuration and with up-struck lugs or fingers 27 employed to retain a cap 28 in FIG. 3 or 30 in FIG. 6, which cap may be of metal, plastic or other material and transparent as in the other embodiments if desired.

Auxiliary head 24 may be made similar to that of FIGS. 3 and 4 except that instead of a relatively small cap 28 held by fingers 27, it may be glued or spot welded directly to the top of flange 26 or it may be a larger cap 30 secured in the same manner. The auxiliary heads such as those of FIGS. 1, 3 and 6 may be produced in strip form and joined by a weakened line.

The nail for a wooden deck is illustrated in FIG. 7, in which event the shank is of uniform diameter and provided with vertical ribs 10A which guide the auxiliary head relative to the shank and mounted to reduce the possibility of the parts being bound together due to rusting or the accumulation of foreign matter between the surfaces, the vertical ribs increase the size of the shank making it possible to manufacture the nail inexpensively from wire with an enlarged diameter along the portion having the vertical ribs. This enlarged diameter is desirable to provide a tight fit regardless of any enlargement caused by the cutting of the shank in the formation of the nail in this or another manner.

In the practice of the invention insulation is fastened tightly against a deck or support over which layers of felt are placed and these are given a coat of asphalt or tar and the driven fastener or nails of the present invention are applied being driven by an ordinary hammer with other types of nails, the layers of felt would be punctured by the head of conventional nails upon the application of pressure sufficient to compress the insulation near the head of the nail or by the application of a person's foot, a wheel barrow or other object.

When the nail is driven by a conventional hammer the last blow of the hammer drives both the large and smaller nail heads downwardly compressing the insulation and driving the large head below the normal level of the top surface of the insulation, the raising and lowering movement of which is about $\frac{1}{4}$ inch and corresponds substantially to the depth of the concealed well within which the auxiliary head is disposed.

With applicant's movable head nail the felt is not punctured because it moves downwardly when force is applied thereto sufficient to compress the felt and it returns to its initial position when the pressure is relieved. Applicant's device therefore is suitable for attachment to a metal or wood deck to secure flexible insulation thereto in a manner to permit such insulation to be compressed and the head of the fastener to move with it.

In the construction of roofs it is customary to apply a fire-proof sheet next to the deck to provide a vapor barrier and on this to place flexible insulation slabs with tar paper on top of the same and to nail through the tar part of the flexible insulation slab and vapor barrier sheet directly into the deck, the nails, however, sometimes leave openings through which heated asphalt could flow into the building. In order to undertake to improve the qualities of the roof a double mopping of asphalt has been employed.

The use of applicant's nail or driven fastener eliminates the necessity of a double asphalt mopping as an adhesive to bond the vapor barrier to the deck and the flexible insulation slab to the vapor barrier and minimizes the possibility of flammable asphalt flowing due to heat through the nail openings into the interior of a building in case of a fire within the building. Applicant's driven fastener or nail hermetically seals as it penetrates the deck and firmly fastens the insulation and a vapor barrier to the deck in one operation so that there is no vapor leakage at the penetration points.

It will be obvious to those skilled in the art that various changes may be made in the invention without departing from the spirit and scope thereof and therefore the invention is not limited by that which is illustrated in the

drawing and described in the specification, but only as indicated in the accompanying claims.

What is claimed is:

1. A fastener for attaching relatively thick resilient insulation of fiberglass or other material, having the ability to spring back after being subjected to pressure, to a deck or other supporting structure, said fastener comprising a shank having a driving point at one end and its other end of a slightly larger diameter to provide a head, an auxiliary head on said shank having a relatively large thin substantially flat flanged portion with a tubular relatively thin walled portion of substantially uniform internal diameter and substantially normal thereto and of substantially greater axial length than said fastener head in which the head of the shank is received in a manner to move freely therein and be guided and supported thereby against lateral movement, and an additional thin walled tubular portion secured to and extending from said portion of substantially uniform internal diameter a substantial distance along said shank and of a diameter snugly to fit, guide and support said shank and serving to maintain it and said shank in driving relation relative to said auxiliary head, there being a small transition between said portion of uniform internal diameter and said extension offering minimum resistance to the penetration of the auxiliary head into the material into which the fastener is driven, the extremity of said thin walled tubular portion offering minimum resistance to penetration of the auxiliary head into the material into which the fastener is driven, the flange on the auxiliary head providing an enlarged driving area on its surface remote from said shank, said auxiliary head having an opening through said flanged portion of larger diameter than said fastener head and aligned with said tubular portions through which the shank portion can be inserted and a closure for said opening secured to the part of the device in which said opening is located.

2. The structure of claim 1 in which said auxiliary head includes a marginal flange retaining the closure for the head.

3. The structure of claim 1 in which said auxiliary head includes portions overlying said closure at its margin.

4. The structure of claim 1 in which said auxiliary head includes portions overlying said closure completely around its margin.

5. The structure of claim 1 in which said auxiliary head includes portions overlying said closure at spaced intervals along its margin.

thereby against lateral movement, and an additional thin walled tubular portion extending from said portion of substantially uniform internal diameter a substantial distance along said shank and of a diameter snugly to fit, guide and support said shank and serving to maintain it and said shank in driving relation relative to said auxiliary head, there being a small transition between said portion of uniform internal diameter and said extension offering minimum resistance to the penetration of the auxiliary head into the material into which the fastener is driven, the extremity of said thin walled tubular portion offering minimum resistance to penetration of the auxiliary head into the material into which the fastener is driven, the flange on the auxiliary head providing an enlarged driving area on its surface remote from said shank, said auxiliary head having an opening through said flanged portion of larger diameter than said fastener head and aligned with said tubular portions through which the shank portion can be inserted and a closure for said opening secured to the part of the device in which said opening is located.

3. The structure of claim 2 in which said auxiliary head includes a marginal flange retaining the closure for the head.

4. The structure of claim 2 in which said auxiliary head includes portions overlying said closure at its margin.

5. The structure of claim 2 in which said auxiliary head includes portions overlying said closure completely around its margin.

6. The structure of claim 2 in which said auxiliary head includes portions overlying said closure at spaced intervals along its margin.
